UNITED STATES PATENT OFFICE.

NICHOLAS A. McMANUS, OF NEW YORK, N. Y., ASSIGNOR TO ITHACA WALL PAPER MILLS, A CORPORATION OF NEW YORK.

DESIGN FOR WALL-PAPER.

SPECIFICATION forming part of Design No. 35,735, dated February 11, 1902.

Original application filed January 4, 1902, Serial No. 88,474. Divided and this application filed January 10, 1902. Serial No. 89,242. Term of patent 3½ years.

To all whom it may concern:

Be it known that I, NICHOLAS A. McMANUS, a citizen of the United States, residing at New York city, in the county of Richmond and State of New York, have invented and produced a new and original Design for Wall-Paper, of which the following is a full, clear, and exact specification.

This application is a division of application filed January 4, 1902, and having Serial No. 88,474.

The figure shown on the drawing is a plan view of my new design for wall-paper, showing it to be adapted to be used as a ceiling covering.

As shown in the drawing, the leading or material feature of my design consists of the central panel 1 and the wreaths 2 and the festoons 6 of flowers surrounding it. The cen-

tral panel consists of the flower 4, supported by the scrollwork 5. The wreaths 2 are diagonally opposite the flowers 4 and the supporting scrollwork 5 and are connected with the scrollwork by the sprays of conventionalized flowers 6. Diametrically opposite the flower 4 and the scrollwork 5 are the wreaths 7, connected with the wreaths 2 by the sprays 8.

Having thus described my invention, I declare that what I claim as new, and desire to secure by Letters Patent, is—

The design for wall-paper as herein shown and described.

In testimony whereof I affix my signature in presence of two witnesses.

NICHOLAS A. McMANUS.

Witnesses:
